WALL STAND

Echo E. Svic, Wauwatosa, Wis.

Application December 31, 1952, Serial No. 22,939

Term of patent 7 years

(Cl. D33—3)

To all whom it may concern:

Be it known that I, Echo E. Svic, a citizen of the United States, residing at Wauwatosa, State of Wisconsin, have invented a new, original, and ornamental Design for a Wall Stand, of which the following is a specification, reference being had to the accompanying drawing, forming a part hereof.

Figure 1 is a perspective view of a wall stand, showing my new design;

Figure 2 is a perspective view similar to Figure 1 but showing the cabinet door in an open position; and

Figure 3 is a side elevational view of the wall stand as shown in Figure 1 of the drawings.

I claim:

The ornamental design for a wall stand, as shown.

ECHO E. SVIC.
